(57) **CLAIM**

The ornamental design for a display device for programmable controller, as shown and described.

DESCRIPTION

FIG. 1 is a front view showing our new design for a display device for programmable controller;

FIG. 2 is a bottom plan view of the display device for programmable controller of FIG. 1;

FIG. 3 is an enlarged front elevation view within the rectangular area designated as 3 in FIG. 1;

FIG. 4 is a greatly enlarged front elevation view within the rectangular area designated as 4 in FIG. 3;

FIG. 5 is an enlarged bottom view within the rectangular area designated as 5 in FIG. 2;

FIG. 6 is a greatly enlarged view within the rectangular area designated as 6 in FIG. 5; and,

FIG. 7 is a perspective view of FIG. 4.

The broken lines represent environmental structure which is not a part of the claimed design. The dotted chain lines represent a boundary between the claimed design and the unclaimed environmental structure.
